CLAIM

The ornamental design for a video cassette case, as shown and described.

DESCRIPTION

FIG. 1 is a front view of a video cassette case, showing my new design;

FIG. 2 is a left side view thereof;

FIG. 3 is a right side view thereof;

FIG. 4 is a rear view thereof;

FIG. 5 is a top view thereof; and
FIG. 6 is a view similar to FIG. 1 showing a modified form of my new design wherein the only change is the transparent window shown.

The bottom view is omitted as it is symmetrical with the top view.
